SEAL

Filed Dec. 21, 1949

UNITED STATES PATENT OFFICE

2,644,711

SEAL

Theodore Frankel, New York, N. Y.

Application December 21, 1949, Serial No. 134,251

3 Claims. (Cl. 292—322)

1

This invention relates generally to sealing devices of the type which once closed may be opened only by mutilating the same, to thereby indicate that the seal has been broken if an attempt is subsequently made to re-close the seal.

Devices of this character are usually employed in connection with merchandise for the purpose of attaching a tag to the latter, so that removal of the tag necessitates the mutilation of the sealing device. The sealing device may also be used in association with the binding on a package by engaging the sealing member with the opposite ends of the string or twine to thereby afford means for detecting the opening of the package. The purpose of such sealing devices, broadly stated, is to prevent tampering with goods, or the removal of tags or the like therefrom, without positive detection.

An object of this invention is to provide a seal of the above character which is so constructed that when it is once closed, a re-opening thereof may only be achieved by substantial mutilation of the seal, thus providing positive evidence of such reopening.

A further object of this invention is to construct a seal of the character described formed from a single blank of material.

Another object of this invention is to provide a seal of the character described so formed as to provide the maximum gripping area between the several parts to thereby discourage the prying open of the seal.

Still another object of this invention is to provide a seal of the character described in which positive gripping of the several parts to prevent re-opening of the seal is effected without the necessity of deforming the structure of the seal, thereby facilitating the closing and locking thereof, and in which re-opening, after the seal is once closed, may be effected only by mutilation thereof.

Finally, an object of this invention is to provide a seal of the character described in which the locking elements are completely hidden when the seal is closed to thereby prevent re-opening of the seal without substantial mutilation, and in which the construction is simple, sturdy and relatively inexpensive to permit the widest use of the device.

With the foregoing objects and other features and advantages in view, which will appear as the description proceeds, the invention resides in the combination and arrangement of parts and in the details of construction hereinafter described and claimed, it being understood that

2

various changes and modifications may be effected within the scope of the invention as defined by the claims, and without sacrificing the advantages thereof.

5 In the drawing:

Figure 1 is a plan view of a seal constructed according to an embodiment of my invention illustrated in the open position,

Figure 2 is a side view of the seal illustrated in Figure 1,

Figure 3 is a longitudinal sectional view taken on the line 3—3 of Figure 1,

Figure 4 is a plan view of a blank from which the seal shown in Figure 1 is formed,

15 Figure 4a is a fragmentary perspective view illustrating a step in forming the seal from the blank shown in Figure 4,

Figure 5 is a fragmentary sectional view taken on the line 5—5 of Figure 1,

20 Figure 6 is a fragmentary sectional view taken on the line 6—6 of Figure 1,

Figure 7 is a fragmentary sectional view taken through the locking elements as the seal is moved towards closed position,

25 Figure 8 is a fragmentary sectional view similar to that of Figure 7 just prior to the positioning of the seal in fully closed position,

Figure 9 is a fragmentary sectional view similar to Figure 7 showing the locking elements with the seal in fully closed position.

Figure 10 is a perspective view of the seal illustrated in Figure 1 and shown in closed position applied to the free ends of a length of string or twine and partly broken away,

30 Figure 11 is a fragmentary sectional view taken on the line 11—11 of Figure 10, and

Figure 12 is a fragmentary plan view of a blank from which a modified seal may be formed.

Referring to the drawing, and initially to Figure 4 thereof, a blank B is illustrated from which a sealing device constructed according to an embodiment of this invention may be formed. The blank B includes a pair of lozenge-shaped plates 11 and 12 respectively, disposed in end to end relationship, and connected together, at the adjacent acutely angled points thereof by an integral web 13. The outer, or remotely disposed, acutely angled points of the plates 11 and 12 are squared off as at 14 and 15 respectively, and inwardly directed slots or cuts 16 and 17 are formed in each of the several corners of the plates 11 and 12. The edges of the plate 11 are then bent at right angles to the plate along the fold lines 18, of Figure 4, to provide the peripheral edge flanges 19. The tabs 20, on each

of the opposite ends of the flanges 19 are bent inwardly, to abut the inner surface of the next adjacent flange, as best seen in Figure 4a. The longitudinal edges of the flanges 19 are reverted outwardly, and inclined relative to the flanges 19, to provide the rims 21. The top edge of the flange formed along the squared off end 16 of the plate 11 is reverted inwardly, in the direction of the arrow shown in Figure 4a, to overlie the tabs 20 formed on the end of the adjacent flanges 19. The edges of the rims 21 are formed with the toothed projections 22. The marginal edges of the plate 12 are similarly bent at right angles to provide the flanges 23, and the top edges of these flanges are reverted and inclined inwardly to form the rims 24. As seen in Figure 7, the rims 21 and 24 are disposed in substantially parallel planes, when the plates are swung towards each other for closing of the sealing device. The plates 11 and 12 are so dimensioned with respect to each other that the flanges 19 are capable of telescoping within the flanges 23.

Figures 7 through 9 illustrate the operation of the sealing device, and more specifically the manner in which the plates 11 and 12 are locked together to prevent opening thereof without mutilation of the device. In Figure 7, the plate 11 has been pivoted about the connection portion or web 13, and is approaching the plate 12. In Figure 8, the inclined rims 21 and 24 have already engaged, and are sliding over each other. As seen in this figure, the flange 19, and the flange 23 are being oppositely resiliently sprung, to permit the passage of the rims relative to each other. In Figure 9, the plates 11 and 12 are shown in their final closed position, in which the flanges 19 and 23 have returned to their normal right angular relationship relative to the plates to which they are attached, and the rim 24 is disposed above the rim 21 and between the latter and the flange 19. The seal constructed according to the above description may be formed of any resilient material such as metal or the like, and preferably of such material in a relatively thin gauge, so that, any attempt to force the plates 11 and 12 open after the rims 21 and 24 have been engaged, will result in substantial mutilation of the parts in order to indicate that such an attempt at opening has been made.

In Figures 10 and 11 I have illustrated a possible use for the sealing device constructed according to this invention. In these latter figures, and in the remainder of the drawing, the sealing device and its several parts, have all been shown on a substantially enlarged scale, and it is to be understood that the actual device is of relatively small size and therefore convenient for use. In attaching the sealing device to the free ends of a string or piece of twine used for attaching a tag or the like to a garment, or for wrapping a package, the free ends 25 and 26 of the string or twine are disposed between the plates 11 and 12, prior to the closing thereof. When the plates 11 and 12 are disposed in closed position, by following the steps illustrated in Figures 7, 8, and 9, the portions of the string 25 and 26 will be clamped between the rims 21 and 24, thereby preventing the removal of the sealing member from the strings. Removal of the sealing member or device from the strings can only be effected by tearing apart the plates 11 and 12, which tearing apart would effect the mutilation of the relatively thin material making up the sealing device.

In Figure 12 I have illustrated a modification

of the sealing device. Figure 12 shows a fragmentary portion of a blank B' from which the modified sealing device may be formed. In the modified device the rims 24a, as well as the rims 21a are formed with toothed edges to thereby increase the gripping of the rims with the strings when the latter are disposed in the position illustrated by Figures 10 and 11.

From the foregoing it is apparent that there has been provided herein an unopenable seal composed of a pair of elongated similarly shaped plates 11, 12, formed of a resilient material, a web 13 connecting the plates along a limited portion of the edges thereof at one end to provide a pivotal connection between the plates, the plates 11 and 12 being formed with telescopic marginal flanges 19 and 23, respectively, continuously along opposite edges thereof, each of the said opposite edges of each plate having the end portions thereof, respectively adjacent the pivotal connection 13 and the respective opposite ends 14, 15, of the plate, inclined at an angle to each other, the outer flange 23 being formed with an inwardly directed locking element 24 on the edge thereof inclining towards the related plate, and the inner flange 19 being formed with an outwardly directed locking element 21 on the edge thereof inclined substantially parallel to the first-mentioned locking element when the plates are in superposed position and located in registration with said first-mentioned locking element so that the locking elements cam against each other as the plates are pivoted to superposed closed position for springing past each other, and with the plates once in said closed position, spring back to their unflexed positions to interengage and thus prevent separation of the plates.

The foregoing description has set forth two preferred embodiments of my invention, which embodiments may be modified and changed within the scope of the invention without detracting from the advantages or features thereof. Having thus described specific embodiments of my invention what I claim and intend to secure by Letters Patent is:

1. An unopenable seal comprising a pair of elongated similarly shaped plates formed of a resilient material, a web connecting said plates along a limited portion of the edges thereof at one end to provide a pivotal connection between the plates, said plates being formed with telescopic marginal flanges continuously along opposite edges thereof, each of said opposite edges of each plate having the end portions thereof, respectively adjacent the pivotal connection and the opposite end of the plate, inclined at an angle to each other, the outer one of the flanges being formed with an inwardly directed locking element on the edge thereof inclining toward the related plate, and the inner one of the flanges being formed with an outwardly directed locking element on the edge thereof inclined substantially parallel to the first mentioned locking element when the plates are in superposed position and located in registration with said first mentioned locking element so that the locking elements cam against each other as the plates are pivoted to superposed closed position for springing past each other, and with the plates once in said closed position, spring back to their unflexed positions to interengage and thus prevent separation of the plates.

2. An unopenable seal according to claim 1, wherein each of said locking elements is formed by a rim extending along the edge of the related

5

flange, at least one of said rims being formed with a toothed edge.

3. An unopenable seal according to claim 1, wherein said plates are lozenge-shaped, and said web is formed integral with one of the acutely angled points of said plates.

THEODORE FRANKEL.
